UNITED STATES PATENT OFFICE.

WALFRID LARSON, OF KINGSBURG, CALIFORNIA.

WATER PUMP.

Application filed September 17, 1921. Serial No. 501,434.

To all whom it may concern:

Be it known that I, WALFRID LARSON, a citizen of the United States, and a resident of Kingsburg, in the county of Fresno and State of California, have invented a new and Improved Water Pump, of which the following is a full, clear, and exact description.

This invention relates to pumps and particularly to an improved form of water pump and has for an object to provide a simple and strong construction capable of lifting a large volume of water quickly a short distance.

Another object of the invention is to provide a water pump which may have the operating parts bodily removed from one well and inserted into another with a minimum effort.

A further object, more specifically, is the provision of an impelling member together with its journals which act to hold the impelling member in proper position without permitting water or sand entering the bearing.

25 In the accompanying drawings—

Figure 1 is a longitudinal vertical section through a pump disclosing one embodiment of the invention.

Figure 2 is a sectional view through Figure 1 approximately on line 2—2.

Figure 3 is a detail fragmentary sectional view through Figure 1 approximately on line 3—3.

Figure 4 is a detail fragmentary perspective view illustrating the way the impeller blades are connected to their side plates.

Referring to the accompanying drawings by numerals, 1 indicates what is known as a well which is a boxing formed of concrete, wood or other material and which has a foundation 2 of concrete or other material provided with an opening or vertical bore 3 merging into the water supply pipe 4. In the accompanying drawings, members 1, 2 and 4 are made from concrete but if desired some of these could be made from wood or other material, as for instance, the boxing or wall 1.

50 In the present instance, it is aimed to provide a simple construction which will lift a large volume of water in a minimum time for a short distance, as for instance, from four to six feet or possibly a little higher. In many irrigating systems now in use, it is necessary to elevate the water

for a few feet only in order to cause the water to flow in the proper canals and over the land as desired. In a system of this kind the elevation of the water is only for a short distance but it is very desirable to elevate a large volume at a minimum cost.

In the present invention, means have been provided which may be arranged at any desired number of points over an irrigating system and in connection with this well an impeller 7 and associated parts are used, said impeller and associated parts being constructed so as to be bodily removed at any time and placed in another well whereby the same operating mechanism may be used to elevate water at a number of different points.

In order to carry out this idea the device is provided with a bearing member 5 which is provided with a side wall 6 having an inclined or rounded annular shoulder 8, a plurality of spokes or webs 9 and a central bearing sleeve 10. The shoulder 8 rests upon a similar annular shoulder 11 formed on the stationary bearing 12, which stationary bearing is an annular sleeve having the shoulder 11 provided as shown in Figure 1 and also an annular flange 13 embedded in the concrete of base 2. The sleeve 10 acts as a bearing for the shaft 14 and is maintained properly oiled by oil from a suitable reservoir 15, which oil passes through a downward pipe 16 and then through a horizontal pipe 17 to the shaft 14.

From Figure 1, it will be noted that the sleeve 10 has an integral upwardly extending section 18 over which the bearing sleeve 19 fits, said bearing sleeve being part of a casting 20 secured to shaft 14 by a set screw 21 or other suitable means and secured to the top plate 22 of the impeller 7 by suitable rivets 23. The sleeve 19 is provided with an annular flange 24, which flange is cut out at 25 (Fig. 3) so that when it is moved vertically downwardly into the well, it may pass the overhanging shoulder or hook 26 preferably formed integral with one of the spokes or webs 9. After it has been properly positioned it will automatically remain in place by the action of gravity and will act as means for connecting the parts together when it is desired to remove the shaft 14, impeller 7 and associated parts including the member 5.

The impeller 7 is provided with not only a top plate 22 but a bottom plate 22', said bottom plate having a central opening 27

which opening is substantially the same size as the bearing member 5. These plates are connected by impelling blades 28 held in place by suitable anchoring rivets 29 (Fig. 4). These rivets are provided with enlarged ends 30 fitting in suitable openings in the respective blades 28 and extending through apertures in the respective plates 22 and 22', said ends being riveted or upset. It will be noted that the bearing member 5 supports the impeller an appreciable distance above the base 2 whereby there will be no danger of the impeller striking any irregularity of the base or any foreign matter accidentally deposited thereon.

In case it should be desired to remove the impeller 7 and associated parts including the bearing member 5 and place the same in another well, the shaft 14 is merely raised and the impeller will be readily elevated. In case the upper structure is formed as shown in Figure 1, the bolts 31 must be disconnected before the shaft 14 and associated parts may be removed. Ordinarily, however, the bolts 31 and the covering plate 32 are not used.

In regard to the covering plate 32, it is to be noted that this structure is shown in Figure 1 and is designed to be used where the pump acts as a force pump to a limited extent. Where it acts merely as an elevating pump, the covering plate or cap 32 may be omitted. When used as shown in Figure 1 it provides a packing gland 33 to make a substantially water tight structure and is held in place by the bolts 31 which also hold the cross bar 32 in place. Suitable blocks 35 are arranged between bar 34 and plate 32 so as to space the bar a sufficient distance upwardly to permit the proper action of the plate 32. The bolt 31 extends through an annular crown 36 which is secured to the wall 1 in any desired manner, as for instance, by a filling of cement or concrete 37. The water elevated passes out the discharge pipe 38 to any desired point. As shown in Figure 2 a large number of bolts 31 are used and the plate 32 is utilized but these bolts are all unnecessary except two for the bar 34 where the plate 32 is eliminated. If desired, a suitable thrust bearing 38' may be used for supporting the pulley 39, which pulley is rigidly secured to a shaft 14 by any suitable means, as for instance, a set screw 40. This pulley is driven by a belt 41, which belt is driven by any suitable power.

The well 1 and associated parts are preferably arranged so that the water in the pipe 4 will flow under the action of gravity until the chamber 42 of well 1 will be filled partially. Preferably, the parts are arranged so that the water will be normally as high as the top of the impeller 7 so that when said impeller is rotated it may lift the water and permit fresh water to be automatically fed in under the action of gravity. Sometimes

the head of water may not be as high as desired and when this occurs, the impeller must draw the water into the chamber 42 and then raise the level of water in the chamber until it flows out the pipe 38. The bore 3 and 70 also the part of the pipe 4 acts as a lower compartment while chamber 42 acts as the upper compartment and the impeller acts as elevating means for elevating the water in chamber 42 and, consequently, to a certain 75 extent acts as suction means for drawing the water from the lower compartment.

What I claim is:

1. In a water elevating device of the character described an impeller comprising a 80 pair of spaced plates, a plurality of curved impelling blades arranged between said plates and connected thereto, and a tubular bearing guiding member connected to one of said plates centrally thereof. 85

2. A water elevating structure comprising an impeller provided with a tubular bearing member, a pair of spaced plates and a plurality of impelling blades connected to the plates, an auxiliary bearing member 90 slidingly fitting into the first mentioned bearing member, means for supporting said last mentioned bearing member, one of the plates of said impeller being formed with an opening at the eye, and means for providing a water passage-way to a point adjacent said eye whereby when said impeller is rotated water will be drawn in through said eye and discharged from the periphery of the impeller. 95

3. A water elevating structure comprising a well formed with a base and an inlet member acting as a lower compartment, a stationary bearing formed substantially as a sleeve and provided with an inner annular shoulder, a second bearing provided with an outer annular shoulder engaging the first mentioned shoulder, said second bearing having a bearing sleeve, an impeller resting on said bearing sleeve, means for interlocking said impeller and said bearing sleeve when the impeller is lifted out of the well, a shaft secured to said impeller and rotatably mounted in said sleeve, and a power member connected with said shaft for rotating the same. 100

4. A water elevating structure comprising a removable bearing having a central bearing sleeve with a tubular projection, a casting having a tubular member fitting over said tubular projection and an impeller rigidly secured to said casting, said casting having an annular flange, said bearing having a hook adapted to fit over said annular flange whereby the casting and impeller may rotate while prevented vertical disengagement, a shaft rigidly secured to said casting and loosely mounted in said journal sleeve, and means for rotating said shaft. 110

120

125

130

5. A water elevating structure comprising a well having connections with a water supply, a crown for said well having an opening, a discharge pipe for said well near said crown, a covering plate secured to said crown, means for rigidly securing said crown to said covering plate, said covering plate having a packing gland arranged cen-

trally thereof, a shaft extending through said packing gland, an impeller rigidly secured to said shaft, removable tapering means surrounding said shaft at the lower end, and power means secured to said shaft at the upper end. 10
